BEET-SLICING MACHINE

Joe R. Urschel and Gerald W. Urschel,
Valparaiso, Ind.

Application January 2, 1953, Serial No. 329,316

13 Claims. (Cl. 146—162)

1

This invention has to do with machines for slicing rollable sliceable articles such as beets from which the foliage and root extensions have been removed, and primarily concerns such a machine which comprises a chute or guide trough along which the beets are successively propelled by an impeller to attain a speed at which the momentum of the beets is sufficient to carry them through a bank of slicing knives for performing the slicing operation.

Because of the slippery surface of beets which have been topped, derooted and blanched, they are difficult to handle and to hold by mechanical means while a slicing operation is being performed thereon. This character of blanched beets in the process of being sliced by commercial canners has been particularly vexatious because accurately formed slices are highly desirable as well as having the slices extend as nearly perpendicularly to the major axis of the beet as possible. Holding the rather fragile blanched and slippery beet properly orientated with respect to slicing knives has been difficult and heretofore incapable of being performed with satisfactory speed. The principal object of this invention is to overcome these difficulties by the provision of a machine and method of beet-slicing by means of which the slicing operation involves rolling the beet along a trough or guide surface which serves to utilize gyroscopic action of the beet for maintaining its principal axis transversely to the direction of movement as it rolls along the guide surface, whereby the beet can be projected by its own inertia and gyroscopic action with sufficient force into a bank of knives while properly oriented with respect thereto that the beet will be sliced at desired parallel planes therein as the beet carries into and through the knife bank.

A more specific object is the provision of a beet-slicing machine wherein there is a beet-guiding trough extending spirally within a plane, the trough having an inner terminus adjacent an axis extending perpendicularly to such plane and having a discharge terminus disposed radially more distantly from such axis and there being an impeller rotatable about the axis and adapted to sweep along the trough for propelling and accelerating a beet while moving it along the trough from the inner terminus toward the outer terminus from which the beet is dischargeable by virtue of its momentum, together with a bank of slicing knives adapted to cut the catapulted beet into slices while accommodating the passage of the slices between the knives.

A further object is the provision in a beet-slicing machine of the above character of a decel-

2

erator for the beet slices in the form of a tortuous chute into which the slices enter as they emerge at high speed from the discharge side of the knife bank.

5 Another object is the provision of a beet-slicing machine wherein a beet impeller rotating at constant speed about an axis adjacent the inner terminus of a spiral beet-guiding trough is adapted to engage a beet which is substantially at rest at such terminus by a section of the paddle adjacent the axis that is moving at relatively slow curvilinear speed to avoid crushing or bruising the beet and to accelerate the beet as it is moved by the impeller along the trough by engaging such beet with impeller portions progressively more distant from said axis and moving at correspondingly greater curvilinear speed whereby the beet attains a substantial speed as it approaches the discharge terminus of the spiral trough.

Still another object is the provision of a slicing knife unit having a novel knife anchorage and tensioning means for holding the knives in echelon formation.

25 The above and other desirable objects inherent in and encompassed by the invention are elucidated in the ensuing specification, the appended claims and the annexed drawings, wherein:

30 Fig. 1 is a perspective view of a beet-slicing machine constructed according to the principles of this invention.

Fig. 2 is a side elevational view of the machine shown in Fig. 1.

35 Fig. 3 is an enlarged perspective view of a knife frame and a plurality of beet-slicing knives secured therein, said knives constituting a knife bank employed in said machine for slicing beets successively propelled against and through such knife bank.

40 Fig. 4 is an enlarged fragmentary view partly in section, showing part of the machine frame, said knife bank, a casing containing a spiral beet-guiding trough for directing beets into the knife bank, and an impeller for propelling the beets along the trough.

45 Fig. 5 is a fragmentary sectional view taken on the line 5—5 transversely of the beet-guiding trough to illustrate the same in transverse section.

50 Fig. 6 is an enlarged transverse section taken in a vertical plane substantially coincident with the impeller rotational axis and in the direction indicated by the arrows associated with the dot-dash line 6—6 in Fig. 4.

55 Fig. 7 is a fragmentary sectional view taken on the line 7—7 of Fig. 4.

Fig. 8 is a fragmentary sectional view taken on the line 8—8 of Fig. 3.

Figs. 9 and 10 are elevational views of complementary knife holding bracket components.

Fig. 11 is a view taken on the line 11—11 of Fig. 10.

Fig. 12 shows the parts of Figs. 9 and 10 assembled with bolts and knives.

With continued reference to the drawings and particularly to Figs. 1 and 2 thereof, the machine can be seen assembled within and upon a frame 10 having a substantially square skeleton top 11 supported at its corners by four upright legs 12, 13, 14 and 15. Any desired number of brace members 16, 17, 18 and 19 may be provided for the legs. A beet-receiving hopper 21 is mounted upon the frame top 11. A side wall opening (not shown) is adapted to feed beets successively from the hopper through a chute 22 onto an inner terminus 23 of a beet-guiding trough 24 formed within side walls 25 and 26 of a circular casing 27. In Fig. 4 the principal portion of side wall 25 has been broken away to expose the inner side of the side wall 26 and the spiral trough complement 28 thereof cooperating with a similarly formed complement 29 in the wall 25 for forming the spiral trough 24; see Fig. 6. Trough 24 is coincident with the plane indicated by the dot-dash line indicated by the reference characters P—P in Fig. 6 and extends spirally from the inner terminus 23, Fig. 4, to an outer terminus 31. This inner guide trough terminus 23 is adjacent to an axis a—a, shown at a point in Fig. 4, about which a beet impeller is rotatable and the beet discharge terminus 31 is disposed more distant radially from such axis. In Fig. 6 the axis a—a can be seen to constitute the principal axis of a drive shaft 33 for the impeller 32.

Referring now to Fig. 6, the circular casing side wall 26 can be seen to have an axial collar-like extension 34 whereon there is an annular flange 35 secured rigidly to a radial flange 36 upon a tubular shaft housing 37 by means of a circle of cap screws 38 of which one is shown. The shaft housing 37 has a horizontal mounting flange 39, Figs. 4 and 6, formed integrally with its lower side secured by bolts 41 to a bracket 42 mounted upon the frame top 11 by a welded connection shown at 42a in Fig. 6.

The impeller driving shaft 33 is rotatively supported upon a ball bearing unit 43 and a needle bearing unit 44 carried within the tubular housing 37. The inner end of the shaft 33 embodies a circular flange 45 constituting a hub for a shank portion 46 of the impeller 32. A pair of cap screws 47 secure the impeller hub 46 to a portion of the flange 45 that is disposed diametrically opposite from a section of such flange to which a semi-circular counterweight 48 is secured by cap screws 49. This counterweight 48 is for counteracting the centrifugal force developed by the impeller 32 and imposed radially upon the drive shaft 33 during rotation of this shaft and of said propeller.

A notch 51 of curved contour is formed in the impeller hub 46 to facilitate entry of beets into the casing 27 from the bottom portion of the chute 22. A beet registering with and coming into contact with the curved periphery of the notch 51 will be part way into the casing 27 and thus be capable of entering all of the way into such casing for resting upon the lower parts of the circular trough complements 28 and 29 before the impeller completes its next revolution whereby the beet thus entering the casing 27 will

be squarely engaged by the impeller shank 46 attendant to being propelled thereby about the axis a—a during the succeeding revolution.

Circular end wall 25 of the casing 27 is attached to and mounted upon the circular side wall 26 in spaced relation with respect thereto by means of a plurality of spacer sleeves 52 and bolts 53 respectively extending through said sleeves and through registering holes 54 and 55 in the walls 25 and 26. Threaded end portions 57 and 58 of these bolts 53 have nuts 59 turned thereunto for drawing the circular walls 25 and 26 firmly against the ends of the sleeves.

Power for driving the impeller shaft 33 is derived from an electric motor M, Fig. 2, which by means of a pulley 61 upon the armature shaft 62 thereof drives a belt 63 trained over such pulley and also trained over a pulley 64 mounted upon and constrained for rotation with the shaft 33.

The spiral shoulders or complements 28 and 29 of the beet-guiding trough 24 extend spirally from the trough inner terminus 23 about the axis a—a while gradually increasing in radial spacing from such axis within the plane extending perpendicularly to the axis a—a and coinciding with the line p—p in Fig. 6. From a position slightly above the plane indicated by the line 5—5 in Fig. 4, a trough 65 is formed by a pair of shoulders or trough complements 66 and 67 constituting downwardly extending extensions respectively from the radially inner terminals of the trough complements 28 and 29. Thus in Fig. 5 it can be seen that the troughs 24 and 65 are in opposed relation to form a beet-guiding passage 68. This passage 68 extends downwardly coextensively with the previously described discharge terminus 31 of the trough 24. The lower part of the trough 24 as viewed in Fig. 4 is formed by shoulders 69 on respective trough extension members 70; see Fig. 7. These shoulders 69 are continuations respectively of the shoulders 28 and 29 of the casing walls 26 and 25. Each of the cast metal extension members 70 comprises a flange 71 at its upper end and secured by cap screws 72 to flanges 71 at the upper edges of notches 74 formed in the casing side walls 25 and 26. Lower edge parts 75 of the cast extension members 70 are held in spaced relation by spacer bolts 75a having reduced-diameter threaded end portions 75b projecting through holes 75c in the lower edge parts 75 and having nuts 75d turned thereonto. Upper vertical sides 73 of members 70, projecting upwardly from the shoulders 69, fit into the notches 74. Thus the trough extensions 70 and particularly the converging shoulders 69 thereof complement the opposed shoulders 66 and 67, Figs. 5 and 7, of the trough 65 in forming the lower part of the beet-guiding passage 68.

A cast bracket 78 comprises a generally rectangular central portion 79 with downwardly extending flanges 81 at opposite edges of said central portion. The lower edges of the flanges 81 are welded or otherwise secured to cross members 19 and 19a respectively of the machine frame 10; see Figs. 1 and 4. Rectangular central portion 79 of the cast bracket 78 is arranged perpendicularly to the beet-guiding passage 68 and contains a rectangular opening 82 which registers with the passage 68. A beet-slicing knife supporting frame 83 is mounted upon the bracket 78 by means of a cap screw 84 of which the shank projects into a notch 85 in an ear 86 projecting from the lower edge of an end plate 87 and a

wing-headed screw 84^a of which the threaded shank extends through a hole 84^b in the bracket portion 79 into threaded relation with a threaded hole 86^b in an ear 86^a projecting from the lower portion of an end plate 88. Frame end plates 87 and 88 which are rectangular are urged apart by four similarly constructed thrust rods 89, 90, 91 and 92 for placing the bank of beet-slicing knives 97 having opposite ends secured to the plates 87 and 88 under tension. Details of the thrust rod 91 and its association with the frame end plates 87 and 88 are illustrated in Fig. 8. The end of this rod 91 adjacent the end plate 87 contains a threaded cross 90^x and is drawn tightly against the inner face of the plate 87 by a cap screw 94. The opposite end of the thrust rod 91 contains an unthreaded recess 90^a wherein there is an anti-friction compression ball 90^b pressed against by the inner end of the threaded shank 90^c of a cap screw 94^a turned into a threaded hole 94^b in the end plate 88. When the cap screw 94^a is rotated in the direction for advancing inwardly through the end plate 88, such end plate 88 will in fact be caused to separate from the plate 87 while the inner end of the threaded shank 90^c bears against the anti-friction ball 90^b, thereby exerting tension in the knives 97 and placing a thrust in the rod 91. Each of the rods 89, 90, 91 and 92 has a cap screw 94 associated with its end adjacent the plate 87 and a cap screw 94^a associated with its end adjacent the plate 88 as illustrated in Fig. 8.

Each of the frame end plates 87 and 88 has a knife holding bracket 95 secured to its inner face. Each bracket 95, Figs. 3 and 4, is assembled from a pair of flat bar-like bracket components 95^a and 95^b shown in detail in Figs. 9, 10, 11 and 12. Bracket component 95^a has a bottom edge 95^c and a vertical inner edge 95^d opposite an outer edge notched to form a series of shoulders 95^e and riser faces 95^f. A series of bolt-receiving holes 121 are drilled horizontally into the component 95^a through the vertical edge 95^d to extend respectively through the riser faces 95^f, excepting that two of such holes communicate through the uppermost riser face which has twice the height of the riser faces therebelow. The lower of the two holes 121 emerging through the uppermost riser face 95^f is counter-bored at 122 at the end adjacent the vertical edge 95^d to receive half of the large diameter mid-section 123 of a double ended bolt 124. Those holes 121 below that receiving the bolt 124 are similarly counter-bored at 125 to receive the heads of bolts 126, and these counter-bores 125 being progressively deeper from uppermost to lowermost so the bolts 126 of equal shank length can project through and beyond their associated riser faces 95^f. A bolt 127 is inserted in the uppermost hole 121. Bracket component 95^b has a lower edge 95^m and an inner vertical edge 95ⁿ. The outer edge of bracket component 95^b also has a series of shoulders 95^e and riser faces 95^f, and this bracket component is also provided with horizontal bores 121 countersunk at 122 and 125 to receive bolt enlargement 123 and the heads of respective bolts 126 as explained with respect to bracket component 95^a.

After all of the bolts 124 and 126 are in place as illustrated in Figs. 9 and 10 the bracket components 95^a and 95^b are assembled with their vertical edges together as illustrated in Fig. 12. Such assembly is maintained by bolts 128 extending through horizontal holes 129 in these bracket components. Each of the brackets 95 thus assembled with the various knife-attach-

ing bolts 124, 126 and 127 is mounted upon the inner face of one of the knife frame end plates 87, 88 by means of cap screws 96 which extend through the associated plates 87, 88 into threaded recesses 131 of such brackets.

While the end plates 87 and 88 are spaced apart the proper distance to place the shanks of bolts 127 apart the same distance as the spacing between the holes at opposite ends of the knives 97, and while the other knife-attaching bolts 124 and 126 of the brackets 95 are similarly placed, said knives are mounted upon the shanks of these bolts as illustrated in Figs. 3, 4 and 12. Nuts 132 are turned onto the ends of the bolts 124, 126 and 127 for holding the knives in place, the center knife being uppermost, the two knives immediately adjacent the center knife being paired with one another and at an equal lower elevation from the center knife, the next pair of knives being at the same elevation next lower from the first pair, etc., in echelon formation as is visible in Fig. 3, and the cutting edges 101 of these knives extending lengthwise thereof and disposed upwardly as illustrated in Fig. 4. Thereupon the cap screws 94^a, Fig. 8, are rotated to separate the plate 88 from the plate 87 and place the knives under sufficient tension to make them incapable of transverse deflection despite their thinness and their short dimension between their cutting edges 101 and their back or opposite edges 101^a. The knife bank unit is now ready for mounting upon the bracket 78 of the machine in the manner hereinabove described.

35 A serpentine slice-receiving and discharge spout 102 has a receiving end 103 registering with the opening 82 in the bracket 78 and has a downwardly curving wall 104 for deflecting the beet slices downwardly through a discharge opening 105 at the opposite end of this spout. Spout 102 is mounted in place by means of a bracket 106 mounted upon its lower side and secured by a fastening device 107 to the frame cross member 16. A second spout holding bracket 108 is secured to its upper side and is secured to the upper portion 11 of the frame 10 by means of a fastening device 109.

Referring now to Figs. 1 and 2, there is shown at one side of the slice discharge spout 102 a knife guard casing 111 secured in place upon the frame member 19^a by a wing-nut fastening device 112. Guard casing 111 has a rectangular opening 113 therein which is traversed by guard bars 114. The opening 113 permits inspection of the bank of knives 97 whereas the bars 114 preclude inadvertent projection of an operator's fingers into the knife bank where they might be injured, if the machine were in operation, by being struck and forced into the knives by a catapulted beet.

60 A similar guard device 111 (not shown) is mounted at the opposite side of the spout 102 and of the knife bank frame 83.

Operation of the machine

The machine is placed in operation by starting the electric motor M whereby power is transmitted from the pulley 61 on the armature shaft 62 of this motor through the belt 63 to the pulley 64 with which the impeller drive shaft 33, Figs. 2, 4 and 6, is constrained for rotation. Shaft 33 is caused to rotate clockwise as viewed in Fig. 4 thus causing the impeller 32 to revolve clockwise about the axis *a*—*a*. Beets, graded as to size, are fed from the hopper 21 downwardly through the chute 22 onto the lower part of the trough form-

ing shoulders 28 and 29 which converge radially outwardly with reference to the axis $a-a$ as can be seen in Fig. 6. The notch 51 in the beet impeller shank 45 facilitates entry of the beets into the space between the lower part of a chamber CH formed between relatively widely spaced central portions CR of the casing end walls 25 and 26. After a beet arrives in registry with the impeller shank 45 while resting upon the lower portion of the trough forming shoulders 28 and 29, Figs. 4 and 6, this shank portion will engage and propel the beet along the trough 24 formed by such shoulders. As the beet is thus advanced along the trough 24 it is guided thereby in a spiral path progressively departing radially from the axis $a-a$ and thereby accelerate from a relatively slow curvilinear speed at the time of contact with the impeller shank to a relatively fast curvilinear speed at the time it is engaged by the radially outer end of the impeller 32 and catapulted thereby downwardly through the guide passage 68. As the beet is thus propelled along the guide trough 24 it rolls upon the radially outwardly converging shoulders 28 and 29 thereof which orient the beet so that the principal axis thereof passing through the opposite regions thereof respectively where the top and root have been removed approximates parallelism with the axis $a-a$. This orientation of the beet is facilitated by a cavity C extending lengthwise of the propelling face PF of the impeller, said elongated cavity having a transverse curvature upon the periphery of the propeller face PF similar to the surface portion of the beets engaged thereby. Therefore at the time the beets are catapulted from the radially outer end of the impeller 32 into the discharge passage 68 they will be spinning about their principal axes which are arranged generally in parallelism with the impeller axis $a-a$ and transversely of the slicing knives 97. This orientation of the beets with respect to the knives is maintained because of gyroscopic force upon these rapidly rotating beets. Thus the beets will be sliced by the knives 97 transversely of their principal axes pursuant to inertia carrying them into and through the knife bank. The beets are cut into parallel slices of uniform thickness corresponding to the lateral spacing of the knives. By arranging the knives in the echelon formation illustrated the centermost knife 97 will first enter the beet and immediately thereafter successive pairs of knives spaced equally from opposite sides of the uppermost knife 97 will successively enter the beet, the knives of each pair entering the beet simultaneously thereby avoiding unequally applied forces which would tend to disturb orientation of the beet. A further advantage of the echelon arrangement of knives is to avoid compression of the beet slices with attendant crushing of the vegetable cellular structure. Moreover this avoidance of gripping or compression of the beet between the knives diminishes resistance to the passage of the beet therebetween, as does the thin character of these tensile knives. A corresponding slower speed is therefore possible for the rotating impeller.

It is desired to gradually diminish the speed of the beet slices emerging from the lower side of the bank of knives 97 through the opening 82. This is accomplished by the sinusoidal spout 102 which gradually changes the course of movement of the slices from a downwardly direction as they emerge from the knife bank to an upwardly direction as these slices slidingly traverse a lower

curved wall W of the spout. The direction of the slices is again reversed as they traverse an upper curved wall W' before being discharged downwardly through the discharge opening 105 into a suitable receptacle, not shown. This changing of the direction of the slices as they pass through the sinusoidal spout 102 diminishes their speed and consequently the impact created thereby when they are discharged from the machine. The whole character of the relatively fragile sliced product is thus made possible.

Having thus described a single preferred embodiment of the invention with the view of clearly and concisely illustrating the same, we claim:

1. In a beet-slicing machine, a beet-receiving and feeding trough having a beet-receiving terminus adjacent an axis and a beet discharge terminus relatively remote from said axis, said trough extending spirally about such axis from the receiving terminus and progressively departing radially from such axis as such trough extends from said terminus to the discharge terminus, said trough having a paddle-receiving slot bisecting the same from said receiving terminus throughout a substantial portion thereof extending toward the discharge terminus, and a beet-propelling paddle rotatable about said axis and extending radially therefrom into said slot.

2. The combination set forth in claim 1 wherein there is a bank of laterally spaced slicing knives registering with said trough adjacent the discharge terminus thereof, the cutting edges of said knives extending transversely of the trough at said discharge terminus and lying within respective planes disposed in parallelism with the axis of the trough at said discharge terminus.

3. The combination set forth in claim 2 wherein the cutting edges of said knives are in an echelon formation with the centermost of said edges disposed nearer to said terminus than the edges on opposite sides of said centermost edge.

4. The combination set forth in claim 2 wherein the planes containing the cutting edges of said knives are substantially perpendicular to said axis about which the paddle is rotatable.

5. The combination set forth in claim 2 wherein there is a sinusoidal slice decelerating passage having a slice-receiving end upon the opposite side of the knife bank from the trough discharge terminus, and said sinusoidal passage being open at the opposite end thereof for discharging the slices therefrom.

6. In a beet-slicing machine, a beet-receiving and guiding trough having a beet receiving inner terminus and an outer discharge terminus and extending spirally from said receiving terminus substantially within a plane to said discharge terminus, said trough also having a beet impeller receiving slot bisecting its inner terminus within said plane and extending lengthwise thereof at least substantially to the discharge terminus, an impeller rotatable about an axis adjacent the inner terminus of the trough and extending perpendicularly to said plane, said impeller being adapted to sweep through said slot pursuant to rotation about said axis, a bank of slicing knives having cutting edges in registry with the discharge terminus of the trough for intersecting articles discharged from the trough through said discharge terminus, and the cutting edges of said knives being in laterally spaced parallelism within respective planes parallel with that occupied by the trough.

7. In a beet-slicing machine, a casing com-

prising a pair of laterally spaced substantially parallel walls, one of said walls having a beet-receiving opening therein, said wall also having a spiral cavity within its inner periphery, the other wall having a spiral cavity within its inner periphery in opposed conformity with the first-named cavity and being effective complementally therewith to form a spiral trough within said walls, said trough having an inner terminus communicative with the beet-receiving opening and also having an outer terminus, said trough extending spirally outwardly from its inner terminus to its outer terminus while also extending about an axis which intersects said opening perpendicularly to the walls; an impeller hub journaled in said casing coaxially with said axis, an impeller constrained for rotation with said hub and extending radially therefrom between said walls for sweeping therebetween through the trough during rotation of the hub, said impeller being adapted to engage and propel a beet along said trough from the inner terminus thereof and for discharging the same through the outer terminus, and a bank of slicing knives disposed adjacent the outer terminus of the trough for intercepting beets discharged from said outer terminus and cutting the same into slices as they pass through the knife bank.

8. The combination set forth in claim 7 wherein in each of said spiral cavities comprises a shoulder extending lengthwise thereof and along which a beet propelled by said paddle can roll while maintaining contact with each thereof by virtue of centrifugal force acting upon said beet, said shoulders converging toward one another while extending transversely of the trough and radially outwardly of said axis.

9. In a beet-slicing machine, a beet-receiving and guiding trough having a beet-receiving inner terminus and a discharge outer terminus, said trough extending spirally outwardly substantially within a plane from the receiving terminus to the discharge terminus, said trough also having an impeller-receiving slot bisecting its receiving terminus within said plane and extending lengthwise of said trough at least substantially to the discharge terminus thereof, an impeller rotatable about an axis adjacent the receiving terminus of the trough and extending perpendicularly to said plane, said trough comprising shoulders extending lengthwise thereof upon respective opposite sides of said slot, said shoulders converging toward said slot as they extend transversely of the trough and radially from said axis, said impeller being adapted to sweep through said slot pursuant to rotation about said axis, a bank of slicing knives having cutting edges in registry with the outer terminus of the trough for intersecting articles discharged from the trough through said discharge terminus, the cutting edges of said knives being in laterally spaced parallelism and being within planes parallel with that occupied by the trough.

10. In a slicing knife unit, the combination of a pair of laterally spaced knife supporting brackets each including a double series of shoulders and risers arranged in V-formation, knife supporting studs projecting outwardly from said risers, a series of linear knives each having means at one end thereof for attaching to the studs in the risers of one of said brackets and each having a series of means at the opposite ends thereof for attaching to the studs in the risers of the other bracket, each knife also having a cutting

edge of which all are disposed toward the upper edges of the risers with which they are respectively associated to provide an echelon arrangement of knife cutting edges, and thrust means spaced transversely from the knives to provide clearance for cuttable objects to approach the knife edges, and said thrust means exerting thrust force urging the brackets apart endwise of the knives for placing the knives under tension.

10 11. In a slicing knife unit, the combination of a pair of laterally spaced knife supporting brackets each including a double series of shoulders and risers in V-formation, said risers being in parallel planes and each having an upper edge 15 adjacent one of said shoulders immediately thereabove, a series of linear knives each having means at one end thereof for attaching to a respective one of the studs in the risers of one of said brackets and each having means at the opposite end thereof for attaching to a respective stud in the risers of the other bracket, each knife also having a cutting edge of which all are disposed toward the upper edges of the risers with which they are respectively associated and said knives 20 also being disposed flatwise against their respectively associated risers to provide an echelon arrangement of knives in parallel planes, and thrust means spaced transversely from the knives to provide clearance for cuttable objects to approach the knife edges while moving perpendicularly to such edges in parallelism with said planes, said thrust means extending in parallelism with the knives in force-transmitting relation with said brackets and exerting thrust force between 25 the brackets for urging them apart endwise of the knives for placing the knives under tension.

12. The combination set forth in claim 11 wherein there are end plates respectively for said brackets, said end plates having opposed inner faces disposed in parallel planes, wherein said brackets each have an outer face assembled respectively flatwise against the inner faces of the end plates, means for attaching the brackets to the end plates in said assembly therewith, and wherein said thrust means is comprised of endwise expansible elements extending between and secured to said plates.

13. The combination set forth in claim 12 wherein each of said brackets comprises components each having a series of the risers and shoulders thereon and an inner edge extending in parallelism with the risers, each bracket component containing a series of stud-receiving bores communicating between the inner edge thereof and respective of the risers, said bores having countersunk large diameter portions adjacent their associated inner edge of their bracket component, headed knife supporting studs having their heads within said counterbores and shanks projecting endwise outwardly of the bores through the risers for attachment of the knives thereto, and means for securing the components of each bracket in complementary assembly with their inner edges in contiguity while the studs are assembled therewith as aforesaid.
